APPARATUS FOR DRYING SLUDGE

Laurence M. Keoughan, Berwyn, Ill.

Application March 18, 1933, Serial No. 661,513

15 Claims. (Cl. 34—34)

The invention relates to a method and apparatus for drying domestic, industrial and similar sewage sludges as well as other material having similar characteristics.

5 More particularly, the invention relates to a method and apparatus adapted for drying sludges and similar material under vacuum at low temperatures.

10 The apparatus may be generally described as a dryer composed of a plurality of tubes and headers, to which steam or similar heating medium is supplied, positioned in a tank wherein a vacuum is maintained.

15 The material to be dried is distributed around and among the tubes and vaporization of its water content takes place at the saturation temperature corresponding to the vacuum in the tank while steam in the tubes condenses at the relatively higher saturation temperature corresponding to the pressure maintained therein. A substantial temperature difference is thus maintained between the inside and outside surfaces of the tubes, thereby effecting a rapid heat transfer from the steam to the sludge or material being dried.

20 In drying sludge by ordinary methods or at atmospheric pressure with any degree of rapidity and economy, relatively high temperatures must be used. This tends to scorch the sludge and drive off and waste valuable volatile constituents and produce gaseous compounds having penetrating and obnoxious odors. In drying the sludge at low temperatures under vacuum, wherein the maximum temperature to which the sludge may be subjected can be definitely controlled, the reduction of gases and obnoxious odors may be reduced to a minimum and the valuable volatile constituents of the product are retained.

25 The moisture content of the sludge having been vaporized at low temperature in the vacuum tank is evacuated by a barometric jet condenser or the equivalent. Of the small amount of gases produced at these relatively low temperatures, the greater portion will go into solution and be carried out with the condensed water vapor and condenser water. The small residue of non-condensable gases being subject to the action of the jets will be mixed with the condenser water by entrainment and likewise carried out.

30 In thus drying sludge under vacuum, the drying is done largely by means of the latent heat of vaporization of the steam in the tubes. Moreover, the temperature of the steam in the tubes being relatively low, comparatively low exhaust

pressures from back pressure or exhaust turbines may be used. Unusual economies may thus be obtained by the combination of this method of drying with the generation of power from high temperature, high pressure steam wherein the major portion of the total available energy is used for power while the low grade and otherwise largely waste energy is utilized for drying. The exhaust steam being confined in the drier tubes, free from contamination by the sludge or vapors in the tank is thereby adapted to be returned as feed water to the high pressure boilers. It also occurs when drying sludge by other methods, particularly by hot gas driers that a large waste of the product occurs due to fine dust particles being carried out by the exhaust gases. Moreover, the product itself tends to liberate large amounts of dust when being handled, thereby producing a serious explosion hazard. In drying sludge at low temperatures under vacuum, the various oils and greases are retained in the dry product substantially in their original forms so that the tendency of the product to break up into fine dust particles and the dust explosion hazard is reduced to a minimum or rendered negligible.

35 Among the objects of the invention is the provision of improved apparatus for utilizing the heat energy of steam to uniformly dry wet sludge without scorching, to a point where the sludge retains its various oil and grease constituents substantially in their original form, thereby adapting the sludge so dried for use as fuel or fertilizer with a negligible dissemination through the surrounding atmosphere of dust particles or 40 unpleasant and unhealthful odoriferous gases.

Another object of the invention is the provision of apparatus for drying wet sludge in a vacuum tank and improved means for preliminary heating and intermittent delivery of the sludge into the vacuum tank under conditions whereby the sludge is explosively spread over the top of a drying pan.

45 Among the further objects of the invention is the provision of apparatus of the kind described which is simple in construction, adapted to be economically manufactured, and in its construction, assembly and use provides improvements and conveniences adapted to practice methods not heretofore employed in the art for the same 50 general purposes.

55 Many other objects and advantages of the construction herein shown and described will be obvious to those skilled in the art from the disclosure given.

To this end, my invention consists in the novel construction, arrangement and combination of parts herein shown and described, and more particularly pointed out in the appended claims.

5 In the drawings, wherein like reference characters indicate like or corresponding parts:

Fig. 1 is an elevational view of apparatus embodying the principles of the invention;

Fig. 2 is a sectional view along the line 2—2 10 of Fig. 1 drawn to a larger scale;

Fig. 3 is a sectional view taken along the line 3—3 of Fig. 2 drawn to a larger scale;

Fig. 4 is a view along the line 4—4 of Fig. 1 15 drawn to a larger scale;

Fig. 5 is a sectional view of the upper end of 20 a tank and a positive feed device connected therewith;

Fig. 6 is a detail sectional view of one of a 25 plurality of members providing bottoms for pans and devices for controlling the passage of sludge therethrough;

Fig. 7 is a side view of the device as shown in 30 Fig. 6;

Fig. 8 is a sectional view along line 8—8 of 35 Fig. 2 drawn to a larger scale;

Fig. 9 is a view along line 9—9 of Fig. 2 drawn to a larger scale;

Fig. 10 is a perspective view of fragmentary 40 portions of a plurality of movable coils comprising a heating device for the sludge;

Fig. 11 is a perspective view of fragmentary 45 portions of a plurality of stationary coils comprising the heating device and providing a pan in which the movable coils are reciprocated vertically;

Fig. 12 is a diagrammatic view of means for 50 actuating the movable coils; and

Fig. 13 is a detail view showing a round or 55 fillet connection of the tubes with the headers forming the drying elements.

Referring now more particularly to the drawings, the numeral 10 generally designates a closed housing providing a vacuum tank into 60 which sludge is fed at the top and after passing through a drying apparatus is discharged in any desired degree of desiccation. The degree of desiccation may be such that the material is suitable for use as fuel under a boiler, as fertilizing material, or for a variety of other purposes.

The tank 10 is supported by a framework 65 comprising a plurality of vertical posts 11 resting upon a floor or pedestals 13. The posts 11 are connected by a plurality of angle members 12 with which the material comprising the tank 10 is connected by welding or by any other suitable means. A tank 14, positioned above the tank 10, is open at the top to the atmosphere and has its bottom converging to form a pair of hoppers 15, the tank 14 and the hoppers 15 providing containers for the sludge or other material to be delivered into the tank 10 for drying.

Steam jackets 42 on the sides of the hoppers 15 provide means for heating the contents of the hoppers prior to admission to the vacuum 65 tank 10. The jackets 42 are connected with a source of steam supply (not shown) through an inlet pipe 43. The steam condenses in the jackets 42 and the condensate is discharged through a pipe 44 and a steam trap 75.

70 Each of the hoppers 15 is provided with an outlet pipe 18 through which the preheated contents are discharged into the vacuum tank 10. The pipes 18 are fastened to the upper end or cover of the tank 10 by angles forming collars 75 19 in register with apertures 61 in the top of the

tank. A positive feed device is provided immediately underneath the pipes 18 for delivering material from the pipes into the vacuum tank 10. The feed device includes a pair of inverted Y-shaped members 20 mounted on the underside 5 of the cover 17 of the vacuum tank 10 and fastened to the tank by means of collars 22. The upper stem portions of the members 20 comprise pipes 21 positioned in register with the apertures 61. A pair of rotors 27, mounted on a shaft 29 10 and fastened thereto by means of keys 30 are positioned one in each of the members 20. A pair of bearings, each comprising a pair of members 23 and enclosing packing 41, are mounted on opposite sides of the tank 10 to provide supports for the projecting ends of the shaft 29. The packing 41 seals the members 23 against flow of air into the vacuum tank 10 around the shaft 29.

The rotors 27 are each apertured to provide 20 three longitudinally extending equally spaced troughs 28 each preferably covering about sixty degrees of arc. The downwardly and outwardly extending arms of the members 20 each form a pipe section 24 connected with conduits 25 and 25 fastened thereto by a pair of collars 26. The pipe sections 24 are so positioned that any two of the troughs 28 may be brought into registry therewith by revolving the rotors 27, the other trough being simultaneously positioned in registry with 30 the pipe 21. The hopper contents flow by gravity through the pipes 18 and 21 and fill the trough 28 in register therewith. By moving the rotors 27 in either direction through one hundred and twenty degrees, the upper trough 28 filled with sludge 35 will be moved to a position where it is discharged through one of the pipe sections 24. The lower troughs 28 in register with the pipes 24 will at the same time be moved to positions where one will register with the pipe 21 and the other with the 40 other pipe 24. Actuation of the rotors 27 in the opposite direction through one hundred and twenty degrees will repeat the trough filling and discharging operation with the difference that the discharge of sludge will be through the other pipe 45 24. A clearance space is provided between the rotors 27 and the members 20 for ease of operation. The sludge contents of the pipes 18 and 20 provide a seal preventing the entrance of air through the space surrounding the rotors 27. 50

The rotors 27 are oscillated through an angle of one hundred and twenty degrees as described by means of a motor 32. Step-down gear mechanism (not shown) and mounted in a housing 33 is operatively connected with the shaft of the 55 motor 32 whereby a shaft 34 connected with the step-down gear mechanism is revolved at a relatively slow rate. A shaft 34 projects from one side of the housing 33 and provides a mounting for a sheave 37 operatively connected with the 60 sheave 38 by a belt drive 39. The sheave 38 is fixedly mounted on a stud shaft 36 on which a disk 35 is similarly mounted. A link 40 connects the disk 35 with the outer end of an arm 31 mounted upon the rotor shaft 29 in a manner 65 whereby one complete revolution of the disk 35 actuates the arm to move the shaft 29 and rotors 27 back and forth through one hundred and twenty degrees. The rate of oscillation of the rotors 27 can be controlled, by the speed of the 70 motor 32 or otherwise, to suit the particular installation and in practice, it is found that six oscillations back and forth per minute are in general satisfactory.

Complete discharge of the sludge material 75

from the troughs 28 is accomplished by reason of the sludge having been preheated in the hoppers 15 to a higher temperature than the saturation temperature corresponding to the vacuum in the tank 10, thereby causing the internal expansion of the sludge in the troughs 28 to abruptly throw the sludge away from the rotors 27. The impetus given to the sludge discharged in the manner described, together with the breaking up of the sludge particles due to its internal expansion, results in relatively wide distribution of the sludge over a drier pan 48 located immediately underneath the outlet ends of the conduit's 25.

The side walls of the pan 48 comprise a plurality of vertical flat stationary coils or headers 51, 52 and 53, arranged in closely spaced edge relation to provide a rectangular enclosure open at its upper end. The upper ends of the vertical headers 51, 52 and 53 are connected with horizontal headers 57 having a plurality of inclined lugs 65 mounted thereon. A plate 56 is fastened to the lugs 65 in any suitable manner to provide an outwardly inclined flange for the pan. The headers 51 are oppositely positioned on two sides of the pan and the headers 52 are positioned on the remaining sides. The headers 53 are angular in shape, as best shown in Fig. 11, to provide closed corners for the pan. A plurality of transversely extending flat tubes 54 arranged in vertical tiers are connected at their ends with the vertical headers 51. The headers 51, 52 and 53 are connected at their lower ends with a round header 58. The connections of the tubes 54 with the headers 51 and of the tubes 76 and 77 with the headers 78 and 79, respectively, are curved to present fibrous material from accumulating at the joints, the curvature being indicated in Fig. 13.

Steam is admitted into the stationary coils and headers comprising the pan 48 through a branch inlet pipe 67 connected with a main inlet pipe 66. The inlet pipe 66 provides a conduit through which wet steam is admitted following its discharge from a high back pressure or extraction turbine of a turbine generator set for the production of electrical power so that the low grade energy, including the latent heat of vaporization of low pressure exhaust steam, is utilized in the drying process.

A pressure reducing valve 74 is provided in the pipe 66 to control the temperature and pressure of the steam in the coils and headers forming the pan 48. The steam thus admitted to the tubes and headers forming the pan 48 is discharged as condensate through a branch pipe 68 after giving off its heat energy in drying the sludge. The branch pipe 68 is connected with a main steam discharge pipe 69 and with a steam trap 85. The pan 48 is supported by a pair of I-beams 50 extending alongside the headers 52 and connected therewith by angles 55 by welding, or the like.

A drier pan 49 is positioned underneath the pan 48 to receive the sludge which has been passed through and partially dried in the upper pan.

The pan 49 is similar in construction and details to the pan 48 and is provided with an upper header 59 similar to the upper header 57 of the pan 48 and is also provided with a lower header 60 similar to the lower header 58 of the pan 48.

Exhaust steam is admitted into the pan 49 through a branch pipe 71 connected with an inlet pipe 70, the latter being controlled by a pressure reducing valve 74 and connected with the same or a different source of steam supply, as is the inlet pipe 66. The steam after passing through

the pan 49 is discharged as condensate through a branch pipe 72 into a main discharge pipe 73 and a steam trap 75. The pan 49 is supported by a pair of I-beams 50 and angle irons 55 in a manner similar to those providing a support for the pan 48.

The vertical tiers of transverse tubes 54 positioned in the pan 48 are in alignment with the corresponding vertical tiers of tubes 54 positioned in the lower pan 49, and a plurality of movable heating elements are positioned between the tubes 54 in each of the pans 48 and 49. The movable heating elements include a plurality of tubes 76 and 77 arranged in vertical tiers in the spaces between the tiers of tubes 54. The tubes 76 are positioned in alternate spaces between the tubes 54 and are connected at their ends by headers 78. The tubes 77 are likewise arranged in vertical tiers in the remaining spaces between the tubes 54 and are connected at their ends by headers 79. The upper ends of the headers 78 in the pan 48 are connected with a round header 80 and the headers 79 in the pan 48 are similarly connected with a round header 81. The lower ends of the headers 78 and 79 in the pan 48 open into round headers 85 and 86, respectively. The headers 80 and 81 are respectively connected with the inlet pipe 66 through flexible pipes 82 and 83 and a branch pipe 84 as best shown in Fig. 4. Condensate is discharged from the movable heating elements through flexible outlet pipes 87 and 88, the latter being respectively connected at one end with the headers 85 and 86 and at the other end with a branch discharge pipe 89 opening into the main discharge pipe 69.

The described movable heating elements, positioned in and in juxtaposition to the upper pan 48, are supported by vertically movable members in a manner that the tubes 76 and headers 78 are reciprocated vertically a predetermined amount and the tubes 77 and the headers 79 are likewise reciprocated vertically, the latter being moved upwardly while the former are being moved downwardly and vice versa. For this purpose, the headers 80 are fastened to the vertical leg of a horizontally extending angle 90 by means of bolts and bars forming clamps 91 and the header 81 is similarly fastened to the vertical legs of the horizontally extending angles 92 by bolts and bars forming clamps 93. A pair of vertically extending channels 95 are fastened at their lower ends to the angles 90 and at their upper ends, the channels are fastened to the ends of a pair of spaced apart channels 96. The channels 96 are oscillated vertically, in a manner hereinafter described, to impart oscillatory movement to the tubes 76, headers 78 and headers 85 positioned in and in juxtaposition to the upper pan 48. The middle portions of the horizontal legs of the angles 92 are fastened to the ends of a pair of spaced apart channels 94 which are similarly oscillated vertically but in the opposite direction to the channels 96 as hereinafter described to correspondingly oscillate the tubes 77, headers 78 and headers 86.

The lower pan 49 is similarly provided with tubes 76 arranged in vertical tiers in alignment with the tiers of tubes 76 in the upper pan 48 and similarly connected at their ends with headers 78. A plurality of vertical tiers of tubes 77 connected at their ends with headers 79 are similarly positioned in the pan 49 in alignment with the corresponding tiers of tubes 77 in the upper pan 48. The upper ends of the headers 78 in the pan 49 are connected with horizontally

extending round headers 120 and the upper ends of the headers 79 positioned in the lower pan 49 are correspondingly connected with horizontal headers 119. The upper headers 120 are fixedly fastened to the lower headers 85 of the movable elements in the upper pan 48 by plates 121 and clamp bolts 131. The headers 119 are also connected with the lower headers 86 of the movable members of the upper pan 48 by clamp plates 121 and bolts 131. The described connection of the corresponding movable elements of the pans 48 and 49 causes the movable elements of the two pans to be reciprocated in unison and in the same manner.

The vertical headers 78 and 79 positioned in the lower pan 49 are connected at their lower ends with horizontal headers 125 and 124, respectively. Steam is admitted into the pan 19 through the movable headers 119 and 120 which are respectively connected by flexible pipes 122 and 123 with the pipe 70 through a branch pipe 84 similar to that shown as connected with the steam inlet pipe 66. The exhaust steam admitted into the lower movable elements through the flexible pipes 122 and 123 condenses in the movable elements positioned in the lower tank and the condensate is discharged from the lower horizontal headers 124 and 125 through flexible outlet pipes 126 and 127, respectively. The pipes 126 and 127 are connected with the condensate discharge pipe 73 and a steam trap 75 through a branch pipe 89 similar to that shown in Fig. 4 as connected with the discharge pipe 69. The described steam inlet and condensate outlet connections for the movable elements of both the upper pan 48 and the lower pan 49 adapt the movable elements to be heated by exhaust steam in the same manner and from the same source as the stationary elements comprising the respective pans are heated, the flexible elements being so arranged as to permit vertical reciprocatory movement of the movable heating elements.

The bottoms of the upper pan 48 and of the lower pan 49 each comprise a plurality of elements adapted for oscillation to control the discharge of sludge from the pans. Each of the oscillatory elements comprise an angular plate 137 fixedly fastened on a rod 136 extending parallel to the stationary tubes 54 and to the movable tubes 76 and 77. The rods 136 in the bottom of the pan 48 are rotatably mounted on the vertical legs of angles 135, the angles being fastened to the bottom flanges of the I-beams 50 forming a support for the pan. The rods 136 are held against longitudinal movement by pins 138 and washers 139 positioned between the pins and the vertical legs of the angles 135. The movable elements comprising the bottom of the pan 49 are similarly rotatably mounted on a pair of plates 128 fastened to the bottoms of the I-beams 50 which provide supports for the pan.

Transverse or lateral movement of the movable heating elements and supports therefor is prevented or made negligible by spaced apart vertically extending angles 129 fastened to the plates 128, with the stems of T's 130, which are clamped to the horizontal headers 124 and 125, projecting between the outstanding legs of the angles as best shown in Fig. 8. The angles 129 thereby provide runways permitting vertical movement of the T's 130 along with the movable heating elements to which they are attached and hold such elements against movement horizontally.

The movable elements in the upper portion of 75 the device are likewise held against horizontal

movement by a plurality of bolts 99 having their lower ends extending through the horizontal legs of the angles 90 and 92, the latter being apertured to permit vertical movement of the angles. The bolts 99 are arranged in groups of four and are supported in fixed position by pairs of plates 98, mounted on opposite flanges of I-beams 97, the bolts being arranged to clamp the plates in contact with the beams. The described runways underneath the pan 49 and the bolts 99 positioned above the top of the pan 48 cooperate to permit vertical and to prevent horizontal movement of the vertically movable elements and thereby maintain the alternately arranged tiers of movable tubes 76 and 77 in uniform spaced 15 apart relation to the adjacent tiers of flat stationary tubes 54 between which the movable tubes are positioned.

Any suitable mechanism may be used for raising and lowering the movable heating elements 20 positioned in the pans 48 and 49. Equal and opposite vertical reciprocation of the tubes 76 and 77 is accomplished by fluid pressure actuated means illustrated in the drawings as positioned at the upper end of the vacuum tank 10. A block 101 mounted on a pair of spaced apart I-beams 100 provides a support for the fluid actuated means. The I-beams 100 are arranged in spaced apart relation to the I-beams 97 and are preferably symmetrical relative to the vertical 30 center line through the tank 10 and the pans 48 and 49. The actuating means comprises an upper cylinder 102 and a lower cylinder 103 respectively mounted on the upper and lower sides of the block 101. The cylinder 102 contains a piston 35 104 having a rod 105 projecting from the upper end of the cylinder between the channels 96. The rod 105 is operatively connected with the channels 96 by a pin 108, the webs of the channels providing bars for the ends of the pin. A plate 40 115 and a block 109, positioned on opposite sides of the channel webs, provide additional bearings for the pin 108. The lower cylinder 103 contains a piston 106 and a piston rod 107, the latter being connected by a pin 108 with the spaced 45 apart channels 94 in a manner similar to the connection of the rod 105 with the channels 96.

Movement of the piston 104 upwardly from the position shown in Fig. 5 will correspondingly elevate the channels 96 and the movable elements suspended therefrom, including the vertical tiers of tubes 76 positioned in vertical alignment in alternate spaces between the flat tubes 54 in the pans 48 and 49. Movement of the piston 106 downwardly from the position shown in Fig. 5 depresses the channels 94 and similarly moves downwardly all of the movable elements suspended from such channels, including the vertically aligned tiers of tubes 77 positioned in alternate spaces between the flat tubes 54 in the 60 pans 48 and 49. The described movement of the channels 94 and 96 thereby simultaneously causes opposite vertical movement of all of the tubes 76 and 77 positioned in the pans 48 and 49. Inward movement of the pistons 104 and 106 in 65 their respective cylinders 102 and 103 will correspondingly move the tubes 76 and 77 vertically in the opposite direction from that produced by the outward movement of the pistons.

Fig. 12 diagrammatically illustrates means for 70 simultaneously equally actuating the pistons 104 and 106 in opposite directions. A cylinder 133 is shown as connected with the cylinders 102 and 103 by pipes 112 and 111, respectively. The cylinders 102, 103 and 133 and the pipes con- 75

necting the cylinders are filled with any suitable liquid. The cylinder 133 contains a piston 117 connected by a piston rod 118 with any suitable means (not shown) for reciprocating the piston 117. Movement of the piston 117 downwardly from the position shown will force the liquid out of the cylinder 133 through the pipe 11 into the cylinder 103, thereby lowering the piston 106. Downward movement of the piston 106 in the cylinder 103 will force liquid out of the cylinder 103 and into the lower end of the cylinder 102, resulting in lifting the piston 104. Upward movement of the piston 104 will force liquid from the upper end of the cylinder 102, through the pipe 112, into the cylinder 133 above the piston 117. Upward movement of the piston 117 will result in flow of the liquid in a direction opposite to that described, with the result that the piston 104 will be moved downwardly and the piston 106 will be moved upwardly. The cylinders 102 and 103 are of equal diameters and as a result, the described reciprocating movements of the pistons 104 and 106 are equal.

As shown in Fig. 4, the cylinders 102 and 103 are not concentric, the upper cylinder 102 being arranged at one side of the center of the tank 10 in such a manner that it is concentric with a vertical line through the center of gravity of the movable elements carried by the channels 96. Similarly, the cylinder 103 is positioned at one side of the vertical center line of the tank 10 so as to coincide with the vertical line of the center of gravity of the movable elements suspended from the channels 94.

Sufficiently low vacuum is maintained in the tank 10 to permit the described transmission of heat to the sludge from the low pressure and temperature steam in the vertical and stationary tubes forming the pans 48 and 49 and to draw off the moisture content which has been given off by the sludge as vapor. The vacuum is created and maintained in the tank 10 by a condenser 141 connected with the upper end of the tank by a conduit 140. A steam jet ejector 143 with after condenser is connected with the condenser 141 by a pipe 148 to remove the non-condensable gases, which collect in the top of the condenser, and to discharge the same into the atmosphere or into a receptacle, not shown. Pipes 145 and 146 deliver condenser water into the condenser 141 and a tail pipe 142, connected with the bottom of the condenser 141, discharges the condenser water and condensed steam into any suitable receptacle, reservoir, or the like, providing a water seal 149. The condenser 141 and the ejector 143 are shown diagrammatically only and may be any devices respectively suitable for functioning as a condenser and as an ejector.

The sludge fed as described by the feed device through the conduits 25 into the pan 48 tends to move by gravity downwardly through the spaces between the vertical tiers of flat tubes 54, such downward movement being accelerated by the vertical reciprocation of the tubes 76 and 77 as described. The lower edges of the tubes 76 and 77 provide a flat curve of a width such that there is a space between the adjacent sides of the tubes and the stationary flat tubes 54. The tubes 76 and 77 converge towards their top edges so that as they are moved upwardly, there is only a slight tendency to lift the downwardly moving sludge while the surface presented by the wider lower edges of the tubes tends to force the sludge

downwardly as the tubes descend. The drying of the sludge in contact with and contiguous to both the stationary and movable tubes tends to cause a decrease in the rate of heat transfer from the tubes to the sludge as the sludge moves downwardly. The movement of the tubes 76 and 77 relative to the tubes 74 is such as to prevent adhesion of sludge to any particular tube for a period long enough to cake or dry thereon and thereby avoids the formation of heat insulating deposits. The described movement and spacing of the tubes not only moves the sludge downwardly but also to a certain degree forces the sludge through the spaces between adjacent tubes of the same vertical tiers, thereby effecting complete movement of sludge that might otherwise collect and form objectionable heat insulating deposits. The tapering upper edges of the movable tubes present a pointed surface also preventing the sludge from collecting on the top thereof. The drying effect resulting from the contiguity and contact of the sludge with both the movable and stationary tubes is progressive downwardly. By control of the temperature of the steam and the rate of the movable elements and the sludge, the latter may be delivered from the bottom of the pan 48 at any desired degree of desiccation.

The sludge partially dried as described during its descent through the pan 48, upon reaching the bottom of the pan is forced between the oscillatory elements comprising the rods 136 and plates 137 by contact therewith of the lowermost tubes 76 and 77 of the vertical tiers. As shown in Fig. 6, the lowermost tubes 76 are thrust downwardly between the adjacent elements when the tubes 77 are at their maximum elevation and a quantity of the sludge is thereby discharged. Upon elevation of the tubes 76 and the simultaneous depression of the tubes 77, the lowermost of the tubes 77 will similarly contact with the opposite edges of the plates 137 from those shown as depressed in Fig. 6 and will correspondingly force a more or less definite amount of the partially dried sludge through the bottom of the pan. In the interim wherein none of the tubes 76 and 77 are in contact with the plates 137, the latter will be moved by gravity back to their normally closed position. The vertical reciprocation of the tubes 76 and 77 thereby causes the lowermost tubes to discharge the sludge through the bottom of the pan 48 into the lower pan 49 where the same process is repeated as described for the pan 48.

While a single pan of the kind described may be satisfactorily used to dry the sludge to any desired degree, I preferably use a plurality of pans through which the sludge is progressively fed as the partially dried sludge may thereby be subjected to higher temperature gradients as the drying progresses. The rapidity of drying for a given temperature gradient decreases with the moisture content of the sludge and by providing two or more pans similar to pans 48 and 49, the drying may be effected in the lower pans with the same degree of rapidity as in the upper pans. This is accomplished by maintaining steam in each pan at a higher pressure than in the pan immediately above with the result that the saturation temperature of the steam in the pans is progressively increased in accordance with the diminished moisture content of the sludge. The requisite differential of steam pressures in the respective pans may be maintained solely by manipulation of the control valves 74 when both pans 48 and 49 are connected with the same source of 75

steam supply, or it may also be secured by connecting the individual pans with different sources of steam supply and by manipulation of the control valves.

5 The sludge is discharged from the pan 49 into the downwardly converging bottom of the tank 10 having an outlet controlled by a valve 46, adapted for manual operation to remove the dry sludge, the valve being of any suitable form to 10 provide a seal preventing access of air into the tank.

The condenser 141 is adapted to maintain a vacuum of 26 to 27 inches of mercury in the tank 10 at which vacuum wet sludge is rapidly dried 15 by the steam in the tubes and headers comprising the pans 48 and 49. Steam having as low a pressure as five pounds gauge may be used and steam at a pressure of one hundred pounds gauge may be used without scorching the sludge or releasing 20 odiferous or volatile constituents of the sludge.

Thus, it will be seen that I have provided a novel method and apparatus for drying wet sludge and similar materials under vacuum, whereby low temperature and pressure steam not otherwise 25 available for power can be utilized for rapidly drying the sludge without scorching the sludge or driving off valuable volatile constituents or the producing of gaseous compounds having penetrating and obnoxious odors.

30 Having thus described the invention, it is obvious that various immaterial modifications may be resorted to without departing from the spirit of the invention; hence I do not wish to be limited to the exact form, construction and arrangement 35 of parts herein shown and described, or uses mentioned.

What I claim as new and desire to secure by Letters Patent is:

1. In apparatus of the kind described, a tank, 40 exhauster mechanism operable to maintain less than atmospheric pressure in the tank, a plurality of horizontally extending tubes positioned in the tank, said tubes being arranged in spaced apart vertical tiers, alternate rows of said tiers being stationary and the remaining tiers being 45 movable, means operable to vertically reciprocate said movable tiers of tubes, means operable to deliver sludge into the tank above said tiers in a manner whereby the sludge is distributed between the uppermost tubes of said tiers, and means adapted to deliver steam into said tubes at selected pressures and corresponding temperatures.

2. In apparatus of the kind described, a tank, 55 exhauster mechanism operable to maintain less than atmospheric pressure in the tank, a plurality of horizontally extending tubes positioned in the tank and arranged in spaced apart vertical tiers with the tubes comprising each tier spaced 60 apart vertically, alternate rows of said tiers of tubes being stationary and the remaining tiers of tubes being movable, means operable to vertically reciprocate said movable tiers of tubes in a manner whereby alternate ones of said movable tiers 65 are caused to ascend as the remaining movable tiers are caused to descend, means operable to deliver sludge into the tank in a manner whereby it is distributed between the uppermost tubes of said tiers, and means adapted to deliver steam 70 into said tubes at selected pressures and corresponding temperatures.

3. In apparatus of the kind described, a tank, 75 exhauster mechanism operable to maintain less than atmospheric pressure in the tank, a drier pan positioned in the tank, said pan comprising a

plurality of vertically extending headers forming the side walls of said pan, a plurality of horizontally extending tubes connected with said headers and arranged in spaced apart vertical tiers, a plurality of horizontally extending movable tubes arranged in vertical tiers between said first mentioned tiers, means operable to vertically reciprocate said movable tiers, means operable to deliver sludge into the tank and to distribute the sludge over the top of said pan, and means adapted to deliver steam into said headers and tubes at selected pressures and corresponding temperatures.

4. In apparatus of the kind described, a tank, 15 exhauster mechanism operable to maintain less than atmospheric pressure in said tank, a drier pan positioned in the tank, said pan comprising a plurality of vertically extending headers forming the side walls of said pan, a plurality of horizontally extending tubes connected with said 20 headers and arranged in spaced apart vertical tiers, a plurality of horizontally extending movable tubes arranged in vertical tiers between said first mentioned tiers, means operable to vertically reciprocate said movable tiers of tubes in a manner whereby alternate ones of said movable tiers are caused to ascend as the remaining ones of said movable tiers are caused to descend, means operable to deliver sludge into the tank and to distribute the sludge over the top of said pan, a 30 plurality of plates extending parallel to said tubes and forming the bottom of the pan, individual mounting members adapting said plates for limited oscillation about a longitudinal axis, the edges of said plates being in the path of the 35 lowermost of the tubes forming said movable tiers whereby downward movement of each tier forces contiguous edges of adjacent plates downwardly, and means adapted to deliver steam into said headers and tubes at selected pressures and corresponding 40 temperatures.

5. In apparatus of the kind described, a tank, 45 exhauster mechanism operable to maintain less than atmospheric pressure in said tank, a plurality of horizontally extending tubes positioned in the tank and arranged in groups spaced apart vertically, the tubes of each group being arranged in spaced apart vertical tiers, alternate ones of said tiers in each group being stationary and the remaining tiers being movable, means operable to simultaneously vertically reciprocate the 50 movable tiers of each group, means operable to deliver sludge into the tank above the upper group of tubes, and means adapted to deliver steam into each of said groups of tubes at selected pressures and corresponding temperatures.

6. In apparatus of the kind described, a tank, 55 exhauster mechanism operable to maintain less than atmospheric pressure in said tank, a plurality of drier pans arranged in the tank in spaced apart vertical relation, each of said pans comprising a plurality of vertically extending headers forming side walls for the pan, a plurality of horizontally extending tubes positioned in each pan connected with said headers and arranged 60 in spaced apart vertical tiers, a plurality of longitudinally extending movable tubes arranged in vertical tiers between said tiers of stationary tubes, means operable to vertically reciprocate the movable tiers in each pan in a manner whereby alternate ones of said movable tiers are caused to ascend as the remaining movable tiers are caused to descend, means operable to deliver sludge into the tank and to distribute the sludge 65 over the top of the upper pan, a plurality of plates 70

5 forming the bottom of each pan, said plates extending parallel to said tubes, individual mounting members adapting said plates for limited oscillation about a longitudinal axis, the edges of said plates being in the path of the lowermost of the tubes forming said movable tiers in each pan whereby downward movement of each tier forces contiguous edges of adjacent plates downwardly, and individual means severally adapted to deliver 10 steam into the tubes and headers respectively comprising each pan, said several means for delivering steam to the headers and tubes comprising the respective pans being adapted to deliver steam at relatively low pressures and corresponding 15 temperatures and to deliver steam to each next lower pan at successively higher pressures and corresponding temperatures.

7. Apparatus for drying material of the kind described comprising a tank, exhauster means 20 adapted to maintain less than atmospheric pressure in the tank, a plurality of stationary tubes arranged in spaced apart relation in the tank, a plurality of tubes reciprocally movable in the spaces between said tubes and operable thereby 25 to rub the advancing material over the adjacent surfaces of said stationary tubes, and means adapted to deliver steam into said tubes at selected pressures and corresponding temperatures.

8. Apparatus for drying material of the kind 30 described comprising a tank, exhauster means adapted to maintain less than atmospheric pressure in the tank, a plurality of stationary tubes arranged in the tank in spaced apart tiers, means operable to deliver material between said tubes, 35 a plurality of tubes reciprocally movable between said tiers, the reciprocation of said tubes adapted to advance and rub the material over the adjacent surfaces of the tubes, and means adapted to deliver steam into said tubes at selected pressures and saturation temperatures.

9. Drying apparatus of the kind described comprising a tank, exhauster means adapted to maintain less than atmospheric pressure in the tank, a plurality of tubes in the tank arranged in spaced 45 apart vertical tiers, a plurality of elements reciprocally movable between said tiers adapted to rub the advancing material over the adjacent surfaces of the tubes, a hopper positioned on the tank above said tubes and providing a container 50 for material to be dried, means operable to intermittently move material from the hopper into the tank above said tubes, and means adapted to heat the hopper contents to a temperature such that its internal pressure explosively spreads the 55 material over the spaces above said tubes.

10. In apparatus for drying material of the kind described, a heating device comprising a plurality of stationary tubes arranged in spaced apart vertical tiers, a plurality of tubes reciprocably movable between said tiers, the reciprocation of said tubes being adapted to advance and rub the material over the adjacent surfaces of the tubes, means operable to reciprocate said movable tubes, and means adapted to deliver a 60 heating fluid into said tubes at selected pressures and corresponding temperatures.

11. In apparatus for drying material of the kind described, a heating device comprising a plurality of horizontally extending tubes arranged in spaced apart vertical tiers with the tubes comprising each tier spaced apart vertically, alternate ones of said tiers of tubes being stationary and the remaining tiers movable, means operable to vertically reciprocate said vertical 65 tiers of tubes in a manner whereby alternate 70

ones of the movable tiers are caused to ascend as the remaining movable tiers are caused to descend, and means adapted to deliver a heating fluid into said tubes at selected pressures and corresponding temperatures.

12. In apparatus for drying material of the kind described, a heating device comprising a plurality of stationary, elongated hollow members arranged in spaced apart relation, a hollow member positioned between said stationary members, 10 means operable to deliver material between said stationary members, means operable to reciprocate said movable member in contact with said stationary members and adapted thereby to rub and advance said material over the adjacent surfaces of said members, and means adapted to deliver heating fluid into said members at selected pressures and corresponding temperatures.

13. In apparatus of the kind described, a tank, 20 a drier pan positioned in the tank, said pan comprising a plurality of vertically extending headers forming the side walls of said pan, a plurality of horizontally extending tubes connected with said headers and arranged in spaced apart vertical tiers, a plurality of horizontally extending 25 movable tubes arranged in vertical tiers between said first mentioned tiers, means operable to vertically reciprocate said movable tiers, means operable to deliver sludge into the tank and to distribute sludge over the top of said pan, and means 30 adapted to deliver steam into said headers and tubes at selected pressures and corresponding temperatures.

14. In apparatus of the kind described, a tank, 35 a drier pan positioned in the tank, said pan comprising a plurality of vertically extending headers forming the side walls of said pan, a plurality of horizontally extending tubes connected with said headers and arranged in spaced apart vertical tiers, a plurality of horizontally extending 40 movable tubes arranged in vertical tiers between said first mentioned tiers, means operable to vertically reciprocate said movable tiers of tubes in a manner whereby alternate ones of said movable tiers are caused to ascend as the remaining ones 45 of said movable tiers are caused to descend, means operable to deliver sludge into the tank and to distribute the sludge over the top of said pan, a plurality of plates extending parallel to said tubes and forming the bottom of the pan, 50 individual mounting members adapting said plates for limited oscillation about a longitudinal axis, the edges of said plates being in the path of the lowermost of the tubes forming said movable tiers whereby downward movement of each 55 tier forces contiguous edges of adjacent plates downwardly, and means adapted to deliver steam into said headers and tubes at selected pressures and corresponding temperatures.

15. In apparatus of the kind described, a tank, 60 a plurality of drier pans arranged in the tank in spaced apart vertical relation, each of said pans comprising a plurality of vertically extending headers forming side walls for the pan, a plurality of horizontally extending tubes positioned in each pan connected with said headers 65 and arranged in spaced apart vertical tiers, a plurality of longitudinally extending movable tubes arranged in vertical tiers between said tiers of stationary tubes, means operable to vertically 70 reciprocate the movable tiers in each pan in a manner whereby alternate ones of said movable tiers are caused to ascend as the remaining movable tiers are caused to descend, means operable to deliver sludge into the tank and to distribute 75

the sludge over the top of the upper pan, a plurality of plates forming the bottom of each pan, said plates extending parallel to said tubes, individual mounting members adapting said plates for limited oscillation about a longitudinal axis, the edges of said plates being in the path of the lowermost of the tubes forming said movable tiers in each pan whereby downward movement of each tier forces contiguous edges of adjacent plates downwardly, and individual means sev-

erally adapted to deliver steam into the tubes and headers respectively comprising each pan, said several means for delivering steam to the headers and tubes comprising the respective pans being adapted to deliver steam at relatively low pressures and corresponding temperatures and to deliver steam to each next lower pan at successively higher pressures and corresponding temperatures.

LAURENCE M. KEOUGHAN. 10
